An improved method for preventing XSRF attack on a web site, which has a URL and is accessible from a port on a server. This invention: determines whether a requestor is legitimate; generates a session token for each session on the web site requested by the legitimate requestor; embeds the session token in a session cookie; additionally generates a security token; embeds the security token in the original request URL; and redirects the web site request to the newly formed URL. The subsequent request of the URL containing the security token allows the server to verify the token and serve the web site to the legitimate requestor. In other words the server's web site for that user for that session is: port/security token/URL/ form data.

6 Claims, 3 Drawing Sheets

A statutory invention registration is not a patent. It has the defensive attributes of a patent but does not have the enforceable attributes of a patent. No article or advertisement or the like may use the term patent, or any term suggestive of a patent, when referring to a statutory invention registration. For more specific information on the rights associated with a statutory invention registration see 35 U.S.C. 157.

1

METHOD FOR PREVENTION OF CROSS SITE REQUEST FORGERY ATTACK

BACKGROUND OF THE INVENTION

(1) Field of the Invention

The present invention relates to the field of web application vulnerability and more particularly to prevention of Cross Site Request Forgery attack.

(2) Description of the Related Art

Security tokens guard against a common form of web application vulnerability called a Cross Site Request Forgery (XSRF) attack. This vulnerability utilizes weaknesses in the design of web authentication mechanisms. A web browser is typically authenticated once per browsing session to a secured web destination. The attacker uses that persistent authentication to deceptively initiate requests to an authenticated web destination without the knowledge of the browser user. A XSRF attack commonly takes the form of hidden requests to another secured site within a malicious page. If the viewer of the page with hidden requests had previously visited and authenticated the target site, then the requests initiated by the malicious page will happen transparently to the user. This process can be used to exploit any of the exposed functionality of target site and gather privileged information with the browser user's full privilege level on the target site.

One effective technique to prevent XSRF attacks requires the use of a unique token of data passed between requests from the browser to the target site. By passing unique data between requests, a malicious site is prevented from attacking another web destination because the malicious site will have no knowledge of the required unique data.

A good description of the established best practice approach to prevent XSRF attacks can be seen at "Security Corner: Cross-Site Request Forgeries", published in *php|architect* on 13 Dec. 2004, specifically the part about including tokens in the form data.

Examples

Standard URL

<https://domain.com/path/to/web/application.cgi>

Standard URL including token

<https://domain.com/path/to/web/application.cgi?token=A9DFEZ134ZFYH>

Existing methods of employing this measure require that the target site be designed from the beginning with this technique in mind. In other words, since the token is an argument of the URL the using application must be programmed to accept this token. All pages must handle the token and ensure that links and functionality within the page pass and accept the token of data. While this technique is effective, it requires redesign of legacy web applications and sites. In many cases this redesign can introd

Development of a technique for including security tokens in web authentication mechanism which can be included in all requests and thus obviates the need to reprogram legacy web applications represents a great improvement in the field of web security and satisfies a long felt need of web site programmers, web site operators and the browsing public.

SUMMARY OF THE INVENTION

The present invention is an improved method for preventing XSRF attack on a web site. The web site has a URL and is accessible from a port on a server. This invention: deter-

2

mines whether a requestor is legitimate; generates a session token for each session on the web site requested by the legitimate requestor; embeds the session token in a session cookie; additionally generates a security token; embeds the security token in the original request URL; and redirects the web site request to the newly formed URL. The subsequent request of the URL containing the security token allows the server to verify the token and serve the web site to the legitimate requestor. In other words the server's web site for that user for that session is: port/security token/URL/form data.

A web site has a URL and is accessible from a port on a server. This invention:

determines whether a requestor is legitimate;
generates a session token for each session of the web site requested by the legitimate requestor;
embeds the session token in a session cookie;
communicates the session cookie to the legitimate requestor;

generates a security token;
rewrites the URL to contain the security token,
redirects the requestor to the newly formed URL, and
serves the web site to the legitimate requestor.

The web site has an address of server: port/security token/URL/form data.

In other words, this invention requires a requestor to furnish a security token embedded in the URL before serving the contents of the web site. In this invention, the token is in the URL rather than being included in the form data. This means that only the sewer has to recognize and react to the token. Thus, the application does not have to be programmed or reprogrammed to accommodate the token. Consequently, this invention allows incorporation of increased security without the need to reprogram legacy applications.

An appreciation of the other aims and objectives of the present invention and an understanding of it may be achieved by referring to the accompanying drawings and description of a preferred embodiment.

BRIEF DESCRIPTION OF THE DRAWINGS

FIG. 1 is a diagram showing how connection of the sewer containing this invention to the internet.

FIG. 2 block diagram of the architecture of the server containing this invention.

FIG. 3 is a flow chart illustrating the operation of this invention.

DETAILED DESCRIPTION OF THE PREFERRED EMBODIMENT

While the present invention is described herein with reference to illustrative embodiments for particular applications, it should be understood that the invention is not limited thereto. Those having ordinary skill in the art and access to the teachings provided herein will recognize additional modifications, applications, and embodiments within the scope thereof and additional fields in which the present invention would be of significant utility.

FIG. 1 is a diagram showing connection of the server 14 containing this invention 10 to the internet. Most other users 18 connected to the internet 22 are legitimate requestors who might wish at some point to access the web site maintained on this server 14. The web site has a URL of the standard form, server: port/token/resource. For example <https://domain.com/path/to/web/application.cgi>. One user 26,

however, is malicious and wishes to launch an XSSRF attack on this server **14** and its web site.

FIG. 2 depicts a block diagram of the data processing system **14** (server) containing this invention. The data processing system **14** includes a central processing unit **30** (CPU), an input and output (I/O) INTERFACE **34**, a CLOCK **38**, an operating system **42** (OS), a LOGIC AND CONTROL system **46**, a read only memory **50** (ROM), a random access memory **54** (RAM), a communication port **58**, and a data storage device **62**. The data storage device **62** may be a fast, disk-based data storage device which is well known in the co

One sever **14** useful for this task is manufactured by SUN Microsystems known in the industry as the SUN SPARC processor (e.g., a SPARC 1000) running an SUN SOLARIS operating system **42**. Mother is an International Business Machines Corporation NUMA-Q server (containing an Intel Pentium III CPU) running the Microsoft Corporation Windows NT operating system **42**. A further is a Hewlett-Packard Corporation HP9000 Superdome server (e.g., HP PA-8600) running the HP-UX UNIX operating system **42**.

Database management system software (DBMS) is preferably implemented in a relational database environment such as one produced by ORACLE Corporation known in the industry as the ORACLE 8i relational database management system, or one produced by International Business Machines Corporation known in the industry as the DB2 Universal Database, or one manufactured by Microsoft Corporation known in the industry as the SQL Server relational database management system. It is also contemplated that the data processing system may be a personal computing system such as one manufactured by Dell Incorporated operating with appropriate local processing software applications and in conjunction with local area network (LAN) data connections thus enabling access to distributed computing and storage devices (e.g., databases) as may be required.

The use and operation of the component parts of data processing system **14** including the use and operation of CPU **30**, I/O INTERFACE **34**, CLOCK **38**, OS **42**, LOGIC AND CONTROL **46**, ROM **50**, RAM **54**, COMM PORT **58**, couplings **66**, and data storage device **62** will be readily apparent to those skilled in the field of computers and the like.

The interconnections **66** of the component parts making up data processing system **14** will be readily known in the art of computer system design and implementation. Moreover, the use of a DBMS like ORACLE 8i, including the maintenance, querying, and manipulation of databases and corresponding tables related to a system such as ORACLE 8i, will be as readily understood by those skilled in the art of database management technologies.

COMM PORT **58** is preferably configured to communicate via telecommunications links or some other network topology to other computers **26** via the INTERNET **22**. Electronic communications in the form of data communications will be readily apparent to those skilled in the art. Of course, COMM PORT **58** could be configured to communicate via a networking topology in an open-standards arrangement or in a closed intranet environment utilizing conventional networking protocols such as TCP/IP and the like.

FIG. 3 shows how this invention **10** works. At the start **70** a user requests a protected resource. This will typically be a person trying to access a web site on his computer with a browser. The invention **10** will then determine if the user has proper credentials **74**. If the user does not have credentials

(such as a user id and password), i.e. this is the first time that the user has requested this resource, the system will determine whether the user is a live person or just a computer programmed to crawl the web looking for sites to attack. This step **78**, as is well known to those familiar with web site design, is currently usually done by requesting information from the user (such as, at a minimum, name and email address) and requiring the user to correctly decipher some irregularly formed letters and numbers. In future such determination may be done with retinal or fingerprint scanning or equivalent technology. As is well known, machines are currently incapable of deciphering irregularly formed letters and numbers. So this technique effectively discriminates between live persons and machines.

If the user already has credentials the invention **10** determines **80** whether a session is currently valid. If not, access is denied. If the session is valid the invention **10** determines **82** whether the cookie on the user's browser has a security token valid for this particular session. If the user has a security token valid for this particular session, the user is allowed **100** to log on to the web site.

The only way a user would not have a valid session security token is if it was the user's initial log in for the current session. If the security token is not valid, the invention **10** generates a session security token **90** and a cookie **94**, and communicates **96** these to the user's computer **26** where they are saved by the browser. Then the user is allowed **100** to log on to the web site.

The security tokens feature of this invention provides protection by passing unique data between all requests. Rather than include handling of this data in request parameters or inside of the authentication mechanism, the tokens pass the data within the URL of all requests. The token is appended to the beginning of the URL: the token is parsed out of requests by the web application server and handed off to the authentication layer. In other words, the URL is formulated as follows:

server: port/token/resource

The first element, delineated by a forward slash character following the server and port (optional for standard ports), is set as the token. The elements following the token are what would normally be the URL of the request. Tokens are generated and assigned for each authenticated session. The tokens are randomly generated and recorded on the server.

Examples:

<https://domain.com/cpsess6347821693/path/to/web/application.cgi>

<https://dev.cpanel.net:2087/psess6347821693/scripts4/listaccts>

<https://dev.cpanel.net:2083/cpsess5890816836/frontend/x3/index.html>

This method allows all parts of web applications to utilize security tokens by using relative URLs rather than absolute URLs, a far simpler design pattern than is typically employed to provide unique data tokens.

The following reference numerals are used on FIGS. 1 through 3:

10 method for prevention of cross site request forgery attack of this invention

14 server

18 malicious user

22 internet

26 legitimate user

30 CPU

34 I/O INTERFACE
38 CLOCK
42 OS

70 start
74 credential determination step
78 authentication of credentials
80 determination of validity of current session
82 determination of validity of security token
90 generation of security token
94 generation of cookie
96 communication of security token and cookie to user's browser step
100 web site use

Thus, the present invention has been described herein with reference to a particular embodiment for a particular application. Those having ordinary skill in the art and access to the present teachings will recognize additional modifications, applications and embodiments within the scope thereof.

It is therefore intended by the appended claims to cover any and all such applications, modifications and embodiments within the scope of the present invention.

What is claimed is:

1. An improved method for preventing XSRF attack on a web site, said web site having a URL and being accessible from a port on a server, comprising the steps of:

a) generating a security token for each session of said web site requested by a legitimate requestor;

b) embedding said security token within the URL;
 c) redirecting the legitimate requestor to the URL containing the security token; and
 d) serving said web site to said legitimate requestor.

5   2. An improved method as claimed in claim 1 in which said web site has an address of said server: said port/said security token/said URL.

10   3. An improved method for preventing XSRF attack on a web site, said web site having a URL and being accessible from a port on a server, comprising the steps of requiring a requestor to furnish a security token before serving the contents of said web site; said security token being included in the web site address.

15   4. An improved method as claimed in claim 3 in which said web site has an address of said server: said port/said security token/said URL.

20   5. An improved method for preventing XSRF attack on a web site, said web site having a URL and being accessible from a port on a server, comprising the steps of:

a) determining whether a requestor is legitimate;
 b) generating a session token for each session of said web site requested by said legitimate requestor;
 c) embedding said session token in a session cookie;
 d) communicating said session cookie to said legitimate requestor;
 e) generating a security token;
 f) rewriting the URL to contain the security token,
 g) redirecting the requestor to the newly formed URL, and
 h) serving said web site to said legitimate requestor.

25   6. An improved method as claimed in claim 5 in which said web site has an address of said server: said port/said security token/said URL.
